UNITED STATES PATENT OFFICE.

WILLIAM WHITE, OF NEW YORK, N. Y., ASSIGNOR TO CLARENCE WHITMAN & CO., OF SAME PLACE.

DESIGN FOR A BEDSPREAD.

SPECIFICATION forming part of Design No. 23,488, dated July 24, 1894.

Application filed June 26, 1894. Serial No. 515,790. Term of patent 3½ years.

To all whom it may concern:

Be it known that I, WILLIAM WHITE, a citizen of the United States, residing in the city, county, and State of New York, have invented 5 and produced a new and original Design for Bedspreads, of which the following is a specification, reference being had to the accompanying drawing, which represents a face view of a portion of a bedspread embodying my 10 design, part only being shown in detail, the remainder being shown in outline.

The leading feature of my design is a bedspread ornamented with a series of ovaloidal figures combined to form a rosette ornament 15 with a border presenting a checker-board effect, the whole being of substantially the configuration represented in the accompanying drawing.

In the drawing *a a a* are series of ovaloid 20 curves. Between these curves are series of ovaloids *b b*. Disposed in proximity to these

ovaloids *b b* are ovaloid rosette ornaments comprising ovaloid forms *c c* bordered by circles *d d*; the whole effect being one of a large rosette composed of ovaloidal figures. 25 The border or edging *f* is composed of series of squares presenting a checker-board effect.

Within the field of the bed-spread are interlocked circular bands *e e* with their center space *g* filled in by the representation of a 30 lattice effect; the entire field of the spread within the border and between the ovaloidal figures presenting a hatched or lattice effect or configuration *h*.

What I claim is—

The design for a bed-spread substantially 35 as shown and described.

WILLIAM WHITE.
